Attorney

Inventor

UNITED STATES PATENT OFFICE.

HARRY HILL, OF KIOWA, KANSAS.

TRACE-CARRIER.

No. 895,860.

Specification of Letters Patent.

Patented Aug. 11, 1908.

Application filed April 7, 1908. Serial No. 425,795.

To all whom it may concern:

Be it known that I, HARRY HILL, a citizen of the United States, residing at Kiowa, in the county of Barber and State of Kansas, have invented new and useful Improvements in Trace-Carriers, of which the following is a specification.

This invention relates to improvements in trace carriers, and is designed to provide a novel construction of yoke for connecting a trace carrier of the type shown in my prior Letters-Patent No. 878,393, dated Feb. 4, 1908, and other trace carrier yokes of a similar nature with the hip strap of the harness for supporting the trace therefrom, the specific purpose of the invention being to produce a novel construction of yoke which is adapted to be formed of sheet metal in a strong and durable manner and engaged with a buckle for connecting the same with the hip strap.

The invention consists of the features of construction, combination and arrangement of parts hereinafter fully described and claimed, reference being had to the accompanying drawing, in which:—

Figure 1 is a front elevation of a trace carrier embodying my invention. Fig. 2 is a side elevation thereof, the trace and lower pivot pin appearing in cross-section. Fig. 3 is a central longitudinal section of the carrier. Fig. 4 is a plan view of the blank from which the yoke is made.

Referring to the drawings by reference numerals, 2 designates a clamp, which is designed to be secured to a trace 3 in a manner to prevent it from having any movement thereon. The clamp comprises two members 4, which when in assembled position provide a casing-like structure for the reception of the trace. The lower ends of the clamps 4 are formed to provide hinge knuckles 5, through which passes a pintle 6 to hingedly unite the members. As the members of the clamp are thus hingedly connected together, the clamp may be opened to permit it to be readily and quickly applied to and removed from the trace. The upper ends of the members 4 are formed to provide hinge knuckles 7, through which passes a pin 8, said pin retaining the members in closed position. A yoke 9, comprising a head portion or cross piece 10 and vertical arms or members 11, carries a buckle 12 to engage the lower end of a hip strap 13, the yoke being of novel construction to engage

and hold the buckle, as hereinafter described. The vertical members of the yoke 9 have their lower ends provided with openings 14, through which passes the pin 8, whereby to connect the clamp to the yoke and permit it to be supported from the hip strap 13. One end of the pin 8 is provided with a socket 15 into which fits the free end of a latch member 16, which is pivotally mounted upon one of the vertical members of the yoke 9, and which prevents the accidental displacement of the pin 8.

The manner in which my improved trace carrier may be used may be stated to be as follows:—The yoke 9 is first fastened by the buckle to the hip strap 13 and the clamp 2 applied to the trace, after which the pin 8 is applied to connect the clamp to the yoke, whereby the trace is supported from the hip strap. The members of the clamp are adapted to firmly engage the trace to prevent it from having any movement thereon, and to thereby securely retain the trace in relative position with relation to the hip strap. As before stated, the clamp is adapted to firmly engage the trace, and in order to permit it to be used upon one which is not large enough to permit the clamp to thus firmly engage it, the members 4 thereof are provided with depressions 17 adapted for the reception of packing strips 18.

In view of the fact that the pin 8 secures the members 4 of the clamp in closed position and secures the clamp to the yoke 9, the clamp may be disconnected from the yoke and the members thereof freed to be opened simultaneously, thereby permitting a trace to be readily and quickly detached from a hip strap and the clamp from the trace.

The yoke is formed of sheet metal from the type of blank illustrated in Fig. 4, from which it will be seen that the head portion 9 is provided with straps or extensions 18, which are bent upwardly in parallel relation and provided at their free ends with reduced tabs or fingers 19 bent to provide hooks 20 engaging the cross bar 21 of the buckle carrying the buckle tongue 22. The fingers are longitudinally slotted or bifurcated to receive the inner ends of the tongue, thus adapting them to closely embrace the cross-bar on opposite sides of the tongue, by which the buckle is connected with the yoke in a simple and effective manner. At their points of junction with the head 9 the straps 18 are folded over upon the head to form flanges

23 which stiffen and strengthen the head, as well as permit the straps to come closely in contact and to be mutually reinforced. As a result, a simple, strong and durable construction of supporting yoke is provided to which the buckle is directly connected, and which obviates the necessity of mounting the buckle upon the strap and slotting or otherwise weakening the yoke for the reception of 10 the strap.

Having thus fully described the invention, what is claimed as new is:—

1. In a trace carrier, the combination of a trace-engaging member, a yoke connected therewith and provided with an upward extension having spaced terminal hooks, and a buckle having a cross-bar engaged by said hooks on opposite sides of the tongue mounted thereon.

2. In a trace carrier, the combination of a trace-engaging member, a buckle connected therewith and having a head portion formed with a pair of upwardly bent straps lying in

contact with each other and provided with reduced bifurcated extensions bent to form 25 hooks, and a buckle having a cross-bar engaged by said hooks on opposite sides of the tongue mounted thereon.

3. In a trace carrier, the combination of a trace-engaging member, a buckle formed of 30 sheet metal connected therewith, said buckle having a head provided at its sides with flanges bent over upon the same and having straps extending upwardly from said flanges in contact with each other and formed with 35 reduced terminals bifurcated and bent to provide engaging hooks, and a buckle having a cross-bar engaged by said hooks on opposite sides of the tongue mounted thereon.

In testimony whereof I affix my signature 40 in presence of two witnesses.

HARRY HILL.
